ATTORNEY

UNITED STATES PATENT OFFICE

FRANK PAYNE, OF BILTMORE, NORTH CAROLINA

RAILROAD-CROSSING SIGNAL

Application filed April 9, 1930. Serial No. 442,873.

This invention relates to a railroad crossing signal, the general object of the invention being to provide a system of lights for indicating when the crossing may be made in safety and when a train is approaching the crossing, with means for controlling the circuits of the lamps of the system by a train approaching the crossing, so that the system is an automatic one.

10 Another object of the invention is to provide means whereby the engine crew can see whether or not the system is in operation.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:—

25 Figure 1 is a diagrammatic plan view of the invention.

Figure 2 is a view of the lamp.

Figure 3 is another view of the lamp, but looking toward that side which carries the single window.

30 In this drawing, the letter A indicates the track and the letter B the crossing. A part of the track is insulated from the rest of the track, as shown at 1, the insulated part extending over the crossing, and this insulated

35 portion is connected by a conductor 2 with a source of supply, which may be a line 3 connected to a source of supply, or a battery. A lamp 4 is placed over the crossing or at a point where it can be readily seen by one intending

40 to pass over the crossing and this lamp has two windows 5 in each face thereof which are parallel to the track so that these windows are visible to persons about to pass over the crossing. A horizontal partition 6 divides the

45 lamp casing into two chambers, one of which has the upper windows in its walls and the other of which has the lower windows in its walls. The upper windows each has a green lens therein and the lower ones are provided with red lenses. A lamp bulb 7 is located in

the upper chamber and a lamp bulb 8 is located in the lower chamber. A window 9, containing a clear lens, is formed in each of the sides of the lamp casing facing the track. These windows 9 are located at the center of the casing and the partition is so formed that some of the rays of light from both lamp bulbs can pass through these windows.

Figure 1 shows the system as composed of two lamp casings, one arranged at each side of the track, but it will be understood that but a single lamp casing may be used to control the crossing, but the single lamp must be so placed that it can be seen by persons about to pass over the crossing from either side of the track.

The lamp bulbs 8 are connected by the conductors 10 with the line 3' and by a conductor 11 with that part of the track which is not insulated. The lamp bulbs 7 are connected by the conductors 12 with the line 3 and with a terminal 13, the companion terminal 14 being connected by a conductor 15 with the line 3'. A switch 16 is adapted to bridge the terminals and this switch is connected to an armature 17 of a magnet 18 which is located in the circuit of the lamps 8. A spring 19 normally holds the switch in engagement with the terminals.

Thus it will be seen that when a train passes on to the insulated part of the track, it will electrically connect the conductor 2 with the conductor 11 so that current will flow from the source of supply through the conductors and a part of the train to the lamps 8 so that the red danger signals will be visible to persons approaching the crossing and at the same time, the magnet 18 will be energized to open the switch and thus break the circuits to the lamps 7 which give the green signals. Thus persons approaching the crossing will know that a train is approaching the crossing and that they must not pass. After the train passes the crossing, the wheels of the train, leaving the insulated section of the track, will break the circuit of the lamps 8 and of the magnet and the spring 19 will move the switch to closing position so that the lamps 7 will be lighted. Then the green signals are visible to persons approaching the crossing and such

persons will know that they can safely pass over the crossing. As long as any of the lamps are lighted, the windows 9 will be illuminated so that the engine crew will know the system is in working order when they see the white light from these windows.

Thus I have provided a simple form of signal system for controlling a railroad crossing and one in which the parts are automatically controlled by the trains.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

- 20 1. A railroad crossing signal system comprising a lamp casing having a pair of chambers therein, windows in the walls of each chamber visible to persons approaching the crossing, a red lens in each of the windows of one chamber, a green lens in each of the windows of the other chamber, a lamp in each chamber, circuits for the lamps, means whereby the circuit of the lamp in the chamber having the red lenses in its windows is closed by a train approaching the crossing and the circuit of the other lamp is opened and means for closing the last mentioned circuit and opening the other circuit when the train passes the crossing.
- 25 2. A railroad crossing signal system comprising a lamp casing having a pair of chambers therein, windows in the walls of each chamber visible to persons approaching the crossing, a red lens in each of the windows of one chamber, a green lens in each of the windows of the other chamber, a lamp in each chamber, circuits for the lamps, means whereby the circuit of the lamp in the chamber having the red lenses in its windows is closed by a train approaching the crossing and the circuit of the other lamp is opened, means for closing the last mentioned circuit and opening the other circuit when the train passes the crossing and a window in the casing visible to the crew of a train approaching the crossing and illuminated by the lamps in either chamber.
